UNITED STATES PATENT OFFICE.

CHARLES O. BARLOW, OF NEVADA CITY, CALIFORNIA, ASSIGNOR, BY DIRECT AND MESNE ASSIGNMENTS, OF THREE-FOURTHS TO GEORGE T. EMERY AND JOSEPH W. SPRAGUE, OF SAME PLACE, AND RICHARD H. LANE, OF NEW YORK, N. Y.

MACHINE ROCK-DRILL.

SPECIFICATION forming part of Letters Patent No. 316,107, dated April 21, 1885.

Application filed June 17, 1884. (No model.)

To all whom it may concern:

Be it known that I, CHARLES O. BARLOW, of Nevada City, county of Nevada, and State of California, have invented an Improvement 5 in Machine Rock-Drills; and I hereby declare the following to be a full, clear, and exact description thereof.

My invention relates to certain new and useful improvements in machine rock-drills of 10 that class in which mechanism is employed to deliver a striking or percussion blow.

My improvement consists, primarily, in delivering the blow directly upon the head of the drill-bit, and consequently in mechanism for 15 holding the bit, receiving and controlling its rebound from the rock, and holding it to the rock again, mechanism for rotating it, and mechanism for delivering the blow.

It consists, further, in the various devices, 20 hereinafter explained, by which these results are effected, and also in a device by which the frame or bar carrying the drill and driving mechanism is detached from the feed-screw and adapted to be moved back rapidly.

25 The object of my invention will be made clear in the course of the following description.

Referring to the accompanying drawings, Figure 1 is a perspective view of my drill. Fig. 2 is a vertical longitudinal section of the 30 drill-arbor and its parts, showing the drill-bit in elevation. Fig. 3 is a perspective view of the cross-bar, showing the addition, in some cases, of a second drill-arbor. Fig. 4 is a perspective view of the second arbor, its bearing 35 or seat being open. Fig. 5 is a longitudinal section of same. Fig. 6 is a perspective view of the two-part chuck S. Fig. 7 is a longitudinal section of the detachable nut c on feed-screw C.

40 My improvements I herein see fit to show in connection with a drill of substantially the character shown and described in my application (made jointly with George T. Emery) No. 117,516, filed January 14, 1884, and therefore 45 in referring to the general construction of parts I do not intend to do so with that particularity which would be necessary if I herein for the first time claimed novelty for them.

A is the supporting-column. B is the cross-bar secured to said column by a boxing, a, 50 whereby the cross-bar is adapted to be adjusted vertically and to any desired inclination.

D is the body-bar, provided with a cross-head, d, by which it is suspended from and is adapted to slide upon cross-bar B. This movement is accomplished by means of the feed-screw C, as I shall hereinafter explain.

Mounted in the lower end of the body-bar D is the driving-shaft H, to which power is to be applied in suitable manner, as by the pulley h. Upon this shaft is an eccentric or cam, G, which, through an intermediate cushion, y, and bearing Y', is adapted to force back the hammer-holder I, into which the handle j of hammer J is inserted. The holder is held to 65 its action with the eccentric by means of the arm Y, pivoted rod Z, and spring K. These devices result in the vibration of the hammer to cause it to deliver its blow.

My first and main improvement relates to 70 the manner in which the drill-bit is connected with the machine and receives the blow of the hammer.

An arbor is usually fitted into a seat in the machine, and the blow delivered must be communicated through it and the chuck to the drill-bit. The weight of the arbor and chuck is generally about four or five times the weight of the drill-bit, and I have found that a large percentage of the power applied to the machine is lost, as a great portion of the force of the blow is expended in overcoming the inertia of the drill arbor and chuck.

The object of my first improvement is to do away with the arbor, steel pin, and chuck 85 through which the blow is communicated, and to strike directly on the end of the drill-bit, whereby a much lighter blow will perform the same actual work, and this, of course, means the exercise of less power in operating the machine. In accomplishing this object of striking directly upon the head of the drill-bit certain necessities of the case must be considered. In the first place, means must be provided to hold the bit when in an inclined position, then the drill-bit, being light, will re- 90 95

bound considerably from the rock, and therefore I must provide some means for controlling its rebound and for returning and holding it against the bottom of the rock to receive the next blow, and these means must also be adapted to move on the bit in order that the latter may advance into the hole as it deepens and that the hammer may be moved up to the drill-bit. In the next place, means must be provided for rotating the drill which will also permit its line motion. Accordingly I have the following mechanism:

In the cross-head *d* is loosely seated, in line with the hammer, a hollow arbor, *M*, which is adapted to revolve freely in its seat and to have a slight line movement, Fig. 2. The hollow center of the arbor is larger in diameter than the drill-bit *N*, which passes through it, in order to allow said bit to be drawn out when necessary, notwithstanding its possibly battered head. The forward portion of the hollow center of the arbor is turned out to an increased diameter, and in this portion is fitted an annular elastic clamp or cushion, *O*, preferably a piece of rubber hose embracing the drill-bit. One end of this cushion abuts against the shoulder formed by the increased center, as described, while against its other end the end of an annular gland or nut, *P*, bears. This gland is externally threaded, while the hole into which it fits is internally threaded, so that said gland can readily be screwed in against the cushion to compress it and tighten it on the drill-bit. The outer surface of the forward end of the arbor is threaded to receive a ring, *Q*, between which and the forward end of the arbor-seat in the cross-head *d* is a spring, *R*, preferably an annular band of rubber. The rear end of the drill-bit, which is tempered to prevent its being battered, projects behind the arbor, and is adapted to receive the blows of the hammer *J*. The effect of the blow direct on the head of the drill-bit is to drive it forward in the arbor and in the clamping-cushion *O*. Its rebound is received and broken by said cushion. By means of the gland *P* the tension of the cushion on the drill-bit is so adjusted that the rebound of the drill-bit is communicated through said cushion to the whole arbor, which moves back slightly, the outer spring, *R*, yielding to it momentarily, and then forcing it forward again to throw the drill up against the bottom of the hole, ready to receive the next blow. The tension of the cushion *O* is, however, not great enough to prevent the advance of the drill under the blows it receives, nor great enough, in fact, to make the friction of any importance at all, compared with the advantage of obviating the use of the ordinary reciprocating drill-spindle or arbor and chuck; and the whole machine may, by means of the screw *C*, be moved up on the drill-bit as the latter advances and without stopping its operation. The rear portion of the arbor *M* is cut out to form a rectangular inwardly-tapering socket, in which

the two-part tapering chuck *S* fits, Fig. 2. This chuck consists of two equal plates, in which are made angular grooves conforming to the angular exterior of the drill-bit upon which the said plates fit, Fig. 6. The chuck at its inner end abuts against a washer, *s*, preferably an elastic one, in the base of the socket. A perforated screw-cap, *T*, fits over the rear end of the arbor and presses up against and holds the chuck, Figs. 1, 2. The cap has preferably a thin elastic washer on its inner surface which tightens it to its place when screwed up. This cap adjusts the chuck with sufficient pressure on the drill-bit to cause the rotation of the latter with it, and yet permit its line movement. As the chuck becomes worn the washer *s* is thinned down and the chuck is pushed farther in, its tapering shape and seat causing it to adjust itself properly; or by making the washer elastic it will yield to the adjustment of the chuck. By fitting in a rectangular seat the chuck is of course rotated by the arbor. This rotation of the arbor is effected by means of the endless chain *U*, passing over a chain-pulley, *u*, on the arbor. The chain below passes around a pulley, *v*, operated by a worm-gear, *W*, meshing with a worm (not here shown) on the driving-shaft *H*.

In machines where the drill-bit is long, or where it is working in rock in which it has a tendency to run to one side by reason of the seams or hard or uneven spots in the rock, I find it necessary to duplicate a portion of the devices I have described for the forward portion of the drill-bit. This I show in Figs. 3, 4, 5. From the forward end of the cross-bar *B* extends an arm, *X*, having a semicircular groove in it. To the end of this arm is hinged a swinging cap, *X'*, having a corresponding groove in it, which, with the other groove, forms the bearing or seat for the arbor *M*. The general construction of this arbor and its appendages are similar to those previously described, omitting, however, the chuck and rotating devices, and are designated by similar letters. By throwing back the cap *X'* the arbor may readily be lifted out. The feed-screw *C* passes through a nut, *c*, secured to the cross-head *d* of the body-bar *D*. Now, if this nut were permanently secured to the cross-head, the body-bar could be moved back to withdraw the drill-bit from the hole only by the operation of the screw, which would be a slow and tedious process. To obviate this I provide for the ready disengagement of the nut, whereby the body-bar may be moved back rapidly on the cross-bar. This is done by means of an arm, *d'*, extending forwardly from the cross-head, passing through the body of the nut *c*, and slotted to receive a cross-pin, *c'*, whereby it is held with the nut. By removing the pin the cross-head is freed from the nut and the whole body-bar may be moved back with ease.

Having thus described my invention, what I claim as new, and desire to secure by Letters Patent, is—

1. In a machine rock-drill in which the drill-bit is driven by a blow delivered directly upon its head, a drill-containing arbor seated in the frame or body of the machine, and adapted to have a line movement therein, an elastic cushion or clamp within the arbor and embracing the drill-bit, a screw-gland for tightening the cushion on the drill-bit, and an elastic cushion or spring between the front of the arbor and the frame of the machine, substantially as herein described. 55

2. In a machine rock-drill in which the drill-bit is driven by a blow delivered directly upon its head, a rotating hollow drill-containing arbor seated in the frame or body of the machine, and a two-part tapering chuck in the rear end of the arbor and embracing the rear of the drill-bit, substantially as described. 60

3. In a machine rock-drill having a mechanism for delivering a blow, the hollow arbor M, seated within the frame or body of the machine in line with the blow-delivering mechanism, and the drill-bit N, seated in said arbor and adapted to receive the blow directly upon its head, and a cushion, O, and chuck S, located within the arbor at opposite ends, substantially as herein described. 70

4. In a machine rock-drill in which the drill-bit is driven by a blow delivered directly upon its head, a hollow drill-containing arbor seated within the frame or body of the machine, and adapted to have a line movement therein, a screw-band, Q, on its forward end, and the spring or elastic band or packing R, between said ring and the frame, the annular or elastic cushion or clamp O, seated in its forward end and embracing the drill, and the screw-gland P, by which it is compressed upon the drill-bit, substantially as herein described. 75

5. In a machine rock-drill having a mechanism for delivering a blow, the cross bar B and sliding body-bar D, and the arbors M, seated in suitable bearings, one on said cross-bar at 80 its forward end and the other on the body-bar, said arbors having the clamping-cushions O and the spring-cushions R, substantially as herein described, in combination with the drill-bit N, passing through said arbors and adapted to receive the blow directly upon its head, substantially as herein described. 85

6. In a machine rock-drill, the cross-bar B, feed-screw C, and nut e on said screw, in combination with the body-bar D, carrying the 90 drill-bit and driving mechanism, said bar having a slotted arm, d, passing through the nut and confined by a removable pin, c, substantially as and for the purpose herein described. 95

In witness whereof I have hereunto set my 100 hand.

CHARLES O. BARLOW.
